UNITED STATES PATENT OFFICE.

MCKEE BARCLAY AND FREDERIC W. PARKHILL, OF BALTIMORE, MARYLAND.

STARTER FOR INTERNAL-COMBUSTION ENGINES.

1,396,497.

Specification of Letters Patent.

Patented Nov. 8, 1921.

Application filed January 23, 1920. Serial No. 353,535.

To all whom it may concern:

Be it known that we, MCKEE BARCLAY and FREDERIC W. PARKHILL, citizens of the United States, residing at Baltimore, State 5 of Maryland, have invented certain new and useful Improvements in Starters for Internal-Combustion Engines, of which the following is a specification.

The present invention relates to mechanical starters for internal combustion engines and has for its object the production of a starter which shall be simple in construction, composed of relatively few parts, efficient in operation and easy to apply to either new 15 or already existing engines.

It has for a further object the production of a starter which may be operated from the driver's seat of an automobile by means of a foot pedal.

Another object is the production of such a starter as will act upon the actuation of the foot pedal without any additional operations on the part of the driver.

With these and other objects in view as 25 will more clearly hereinafter appear the invention comprises a mechanism for transforming the longitudinal motion of the foot pedal into a movement of parts at a right angle to the direction of the motion 30 of the pedal and means for utilizing this transverse movement of parts to rotate the crank shaft of the engine. It will be readily understood that, while the drawings and description indicate that the engine shaft will 35 be rotated through a portion of a revolution, the several elements may be so proportioned as to cause rotation of the shaft to any desired extent and even to cause rotation through several complete revolutions.

The invention will be more readily described and understood by reference to the accompanying drawings in which:

Figure 1 shows an elevation of the foot pedal and mechanism adjacent thereto with 45 a portion of the casing inclosing the mechanism removed;

Fig. 2 shows a vertical section through the casing and its contained mechanism along line 2—2 together with the coöperating parts 50 of the device partly in plan and partly in section.

Fig. 3 shows a section along the line 3—3 of Fig. 2.

The invention as indicated by the drawings 55 comprises a housing 1 which is pro-

vided with means, not shown, to allow it to be bolted or otherwise secured to the frame of an automobile or to suitable framework attached to a stationary internal combustion engine. Within the casing 1 there 60 is a pinion 2 which is provided with bosses 2' on either side thereof, which bosses act as bearing members for the pinion in the sides of the casing. The casing is provided in its lower portion with a longitudinal 65 guide 7 in which slides the rack 3 adapted to mesh with and actuate the pinion 2. The rack 3 is carried on the end of a bar 4 which extends a sufficient distance from the casing to allow for the application to the end 70 thereof of a tread 5, the casing and bar 4 being suitably placed to allow the rack to be actuated by the foot of the operator.

Extending transversely through the pinion 2 is the usual axial opening 8 but in the 75 present instance this opening is provided with internal spiral lugs 9, hereinafter referred to as threads.

Mounted within the axial opening 8 in the pinion 2 is a short shaft 11 provided with 80 spiral grooves 10 corresponding to and adapted to coöperate with the threads 9. This shaft 11 is of such size that it will slide freely through the opening 8 but fits snugly therein so as not to allow undue play. 85 The shaft 11 has attached to one end a flexible member 14. This flexible member may be one of several suitable forms and the invention contemplates the use of either a flat steel band, a chain of the sprocket type, or 90 any other suitable form and will hereinafter be referred to as a "strap".

The strap 14 extends around and is attached at its farther end to a drum 16. This drum is loosely mounted on the shaft of the 95 engine. In the drawing the drum 16 is shown as being mounted upon an additional end piece 19 carried on the end of and keyed to the shaft 18 of the engine.

The drum 16 incloses a collar 17 also 100 loosely mounted on the engine shaft and these parts are retained in place longitudinally of the engine shaft by means of a suitable nut 20 or other means well within the skill of the average mechanic.

The collar 17 is provided with a radial bore 21 having mounted therein a bolt 22 which is made of suitable material such as chilled steel, and which is rounded at its ends. A suitable spring acting against a 110

shoulder within the bore is used to prevent the contact of the inner end of this bolt with the shaft of the engine when the parts are in their inoperative position or at rest as indicated in Fig. 2.

It should be noted that the bore 21 is somewhat larger than the bolt 22. This construction is adopted so as to allow side play for the bolt in case of a back-fire. When the 10 starter is operated and the crank shaft is rotated a small distance it sometimes happens that the engine will fire prematurely and kick back. In such cases the sudden jar will cause the bolt which is at such a 15 time in contact with the rounded projection 24 to be thrown or to slip sidewise and accordingly slip past the projection 24 and not unduly shock the starter mechanism and the operator.

20 The drum 16 inclosing the collar 17 is provided on its inner periphery with a rounded projection 24 as indicated in Figs. 2 and 3. This projection 24 is preferably in oval-shaped instead of spherical. Also in 25 the inner periphery of the drum 16 there is provided a groove 25 which extends somewhat more than half way around the drum. This groove is provided to coact with a stop pin 26 provided on the periphery of the collar 17.

30 Suitable springs will be provided for the return of the several parts to their normal inoperative position. Such springs are indicated at 6 on the rack bar and 30 upon the shaft 11.

The drawing shows in addition to the parts already mentioned, that the shaft 11 is provided at the strap end with a rather large head 12 through which, parallel to the 40 shaft, extend the guide rods 13 mounted upon the casing 1. These guide rods are supplied to prevent the rotation of the shaft 11 upon actuating of the pinion by means of the rack. In certain forms of construction 45 these guide rods may be dispensed with. For instance, when the flexible element 14 consists of a rather heavy metal band the guide rods will not be necessary as the resistance to torsion of the band will be sufficient to prevent the shaft rotating more than a very small amount.

Further while the drawing and description show the clutch mounted upon an end piece 19 upon the shaft 18 of the engine, it 55 will be obvious that such end piece may be dispensed with and the drum 16 and collar 17 mounted directly upon the shaft. It will also be obvious that this clutch may be mounted upon the engine shaft not only at 60 the end or either end but may be mounted in any portion of the shaft which may be found convenient, for instance any portion which is not utilized for something else.

In the operation of the one particular 65 embodiment of the invention described and

illustrated, the operator forces the bar 4 inwardly against the tension of the spring 6, which causes the rack 3 to rotate the pinion 2, thereby causing the threaded shaft 11 to slide through the spirally threaded opening 70 8 in the pinion 2. This movement of the shaft 11 causes the head 12, which prevents rotation of the shaft 11, to move along the guide rods 13 against the action of the spring 30. This movement of said head 12 75 gives a pulling action upon the flexible member 14 which is attached at its outer end to the drum 16 loosely mounted on the engine shaft, thereby giving the drum a rotative movement on the engine shaft. 80

As the drum 16 rotates, the bolt 22 is brought in contact with the projection 24, on the inner periphery of the drum, which contact forces the bolt 22 inwardly against the tension of its spring and jams the inner end 85 of said bolt against the engine shaft and thereby firmly clutches the drum to the shaft and effects a turnover of the shaft to start the engine. The pin 26, embedded in the collar 17, traveling in the groove 25, ahead 90 of the bolt 22, when stopped by the ending of the groove, dislodges the bolt 22 and breaks the contact between the drum 16 and the engine shaft. The stoppage of the pin 26 also serves to prevent the continued rotation of the collar 17, which is loosely attached to the engine shaft. When the bar 4 is relieved of pressure, the parts return to 95 normal positions as should now be well understood. 100

Having now described the invention and the preferred form in which it may be constructed it is to be understood that the invention is not limited to the exact form and details given but only to the scope of the 105 appended claims.

We claim:

1. A mechanical starter for internal combustion engines comprising a collar loosely mounted upon the engine shaft, a drum inclosing said collar, clutch means carried by the collar and drum for gripping the shaft, a strap around and attached at one end to the periphery of the drum and having the other end attached to the end of a 110 spirally grooved member which is adapted to move longitudinally through a corresponding internally threaded pinion, and a rack for rotating the gear, substantially as described. 115

2. A mechanical starter for internal combustion engines comprising a foot pedal provided with a rack, a pinion coöperating with the rack, the pinion being provided with an internally threaded axial opening, a correspondingly threaded shaft mounted in said opening and having attached to one of its ends one end of a strap which surrounds and is attached at its other end to the drum of an automatic clutch mounted upon the 120 125 130

shaft of the engine, and means for preventing the rotation of the threaded shaft when said pinion is rotated.

3. The combination with an internal combustion engine of an automatic clutch mounted upon the shaft thereof, a strap surrounding and attached at one end to the incasing drum of the clutch, means attached to the other end of the strap for rotating the shaft of the engine, said means comprising a threaded shaft adapted to be moved longitudinally, an internally threaded pinion surrounding and coöperating with the threaded shaft, a rack for rotating the pinion, the rack and pinion being substantially inclosed within a housing fixed at a suitable distance from the engine shaft, and means for preventing the rotation of the threaded shaft, whereby it is caused to move longitudinally when the pinion is rotated.

4. A mechanical starter for internal combustion engines comprising a foot pedal provided with a rack, a pinion coöperating with

the rack, the pinion being provided with an internally threaded axial opening, a closely 25 threaded shaft mounted in said opening, an automatic clutch mechanism having operative connection with the engine shaft, and a strap connection between the threaded shaft and the clutch mechanism.

5. A mechanical starter for internal combustion engines comprising a foot pedal provided with a rack, a pinion coöperating with the rack, the pinion being provided with an internally threaded axial opening, a closely 35 threaded shaft mounted in said opening, an automatic clutch mechanism having operative connection with the engine shaft, a strap connection between the threaded shaft and the clutch mechanism, and means for preventing rotation of the threaded shaft when 40 said pinion is rotated.

In testimony whereof we affix our signatures.

MCKEE BARCLAY.
FREDERIC W. PARKHILL.
